UNITED STATES PATENT OFFICE.

WALTER M. DANN, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER RADIATOR.

Application filed November 29, 1920. Serial No. 427,190.

To all whom it may concern:

Be it known that I, WALTER M. DANN, a citizen of the United States, and a resident of Wilkinsburg, in the county of Allegheny and State of Pennsylvania, have invented a new and useful Improvement in Transformer Radiators, of which the following is a specification.

My invention relates to heat dissipating devices and it has particular relation to apparatus of the above described character that is adapted for use in connection with electrical or other apparatus normally immersed within a cooling fluid. More specifically, my invention relates to means for cooling the oil or other cooling fluid utilized in transformers, or in other structures in which it is desired to employ a fluid tight type of air cooled radiator.

One object of my invention is to provide a device by means of which the radiator or other cooling member is detachably secured to the fluid containing tank and in which the strains caused by the weight thereof shall be more equally distributed throughout the radiator.

Another object of my invention is to so arrange the connections between the radiator and the tank as to eliminate the necessity of providing special connecting elbows, to reduce the number of joints in said connections and to increase the amount of radiating area of said radiator.

Briefly speaking, my invention consists of constructing the coupling joint between the radiator and the tank upon which it is mounted in such manner that the radiator may be readily detached from the tank without any interference whatever from the adjacent radiator sections.

Heretofore, it has been customary, in the construction of radiators, to provide two spaced common header members having a plurality of radiating units or tubes disposed therebetween and in communication therewith. These header members and associated tubes are usually supported by means of a connection entering one side of the header member. Another supporting structure comprises an arrangement of pipes, including an elbow, which engages the central top portion of the header member, whereby communication is effected with said header members.

One objection to the former type of connection is that in order to disconnect the radiator from the tank, it is necessary for the operator to climb either between, or on top of and underneath, said radiator sections in order to reach the coupling members. If the radiators are relatively close together, as on very large transformers, an operator is prevented from moving therebetween. Also, when supported by one side entirely, the entire weight of the section acts as a lever about the connecting joint, causing excessive stresses therein. An objection to the latter type of structure having a connection in the central portion thereof is that special additional piping sections, including an elbow must be employed, thus necessitating an excessive number of fluid tight joints. Another objection is that such piping connections necessarily occupy considerable vertical space, thereby necessitating the employment of comparatively short radiator sections.

According to my invention, I provide an extruded portion in the top and bottom of said header members whereby a straight short piping connection may be made to the tank. Also, the coupling members are attached together by fastening means disposed without the area of projection of the header member, that is to say out of alignment with said extruded portions in such manner that they are accessible to the operator while standing beyond the perimeter formed by the outer edges of said radiator sections.

In the accompanying drawings, Figure 1 is a front elevational view of a radiator comprising a plurality of header members constructed and connected in accordance with my invention.

Fig. 2 is a side elevational view of the structure shown in Fig. 1.

Fig. 3 is a cross-sectional view of a radiator comprising a single substantially rectangular header member together with its associated supporting couplings, both of which are constructed in accordance with my invention.

Fig. 4 is a view, partially in section and partially in end elevation, of the structure shown in Fig. 3, the section being taken along the line IV—IV thereof.

In Figs. 1 and 2, I show a radiator com-

prising spaced upper and lower header members 5 each provided with apertures in one side thereof adapted to receive heat-dissipating units in the form of cooling pipes 6 and 5 provided at the other side with an extruded portion 7 having an aperture 8 therein. Within each of the apertures 8 is disposed a tubular member 9 secured to the extruded portion 7 by welding or in any other suitable manner and having associated therewith a coupling member 10 having elongated side portions or ear members 11. The ear members 11 are each provided with apertures 12, disposed out of alinement with the extruded portion 7, as best shown in Fig. 1. The radiator units are supported by means of bolts 13 disposed within the apertures 12 which serve to clampingly engage the coupling members 10 of adjacently disposed header members.

The entire radiator section is mounted upon an apertured tank wall 14 by means of a large coupling member 15 associated with the innermost of the radiator units, and a similar coupling member 16 rigidly attached to the tank wall 14. Bolts 17 serve to clampingly engage the coupling members 15 and 16. When assembled, the bolts 17 are disposed out of alinement with the outwardly projecting ears 11 of the coupling members 10, as well as being out of alinement with the extruded portions 7 of the header members, as best shown in Fig. 1. By reason of having the extruded portions 7 relatively 35 narrow and having the bolts 13 and 17 disposed out of alinement therewith, it is possible for the operator to stand at the end of the radiator section and to disconnect the various units from each other, or to disconnect the entire section from the radiator tank, by means of a relatively long socket wrench.

In Figs. 3 and 4, a header member 18 of the rectangular type is illustrated as having 45 attached to one side thereof a plurality of spaced pipes or tubes 19. On the other side 20 of the member 18 is a centrally disposed extruded portion 21, one side of which is provided with an aperture 22. The aperture 22 is adapted to receive a tubular member 23 by means of which it is supported upon and through which it communicates with a tank 27. The member 23 is provided with a coupling member 24 having outwardly projecting side portions or ears 25 disposed out of alinement with the extruded portion 21, as best shown in Fig. 4.

The coupling member 24 is attached to a similar coupling member 26, which is rigidly mounted upon a tank wall 27, by means of bolts 28 disposed within the apertures in the ears 25 of the coupling members 24 and 26. As has been described in connection with Figs. 1 and 2, it is possible for the operator 65 to stand at the outer edge of the radiator

and to remove the bolts 28 from the coupling members 24 and 26 by means of a relatively long socket wrench.

From the foregoing description, it will be apparent to those skilled in the art that among others, the following advantages over the previously employed structures are obtained. The radiators may be disconnected from the tank by any operator standing beyond the perimeter formed by the outer edges of the radiators. The excessive stresses caused by the entire weight of the radiator being supported by a connection disposed at one side thereof are reduced approximately 50% by making the connection in the central portion thereof. The piping connections have been reduced to a minimum and to substantially standard parts. The number of fluid tight joints necessary has been reduced to a minimum. The radiating capacity of the transformer has been increased by permitting an increased length of radiator section, as the amount of space occupied by the radiator connection is reduced to a minimum.

I claim as my invention:

1. A radiator comprising a plurality of heat-dissipating units, a header member provided with a plurality of openings in one side thereof for communication with said units, the opposite side thereof being provided with a centrally disposed extrusion forming a pocket, and means attached to said extrusion for supporting said radiator.

2. A radiator comprising a plurality of heat-dissipating units, a header member provided with a plurality of openings in one side thereof for communication with said units, the opposite side thereof being provided with an extrusion in the form of a pocket having an aperture therein, and a tubular extension engaging said aperture and provided with a coupling member having fastening means arranged out of alinement with said extrusion.

3. A radiator comprising a plurality of heat-dissipating units, a header member provided with a plurality of openings in one side thereof for communication with said units, the opposite side thereof having an extrusion in the form of a pocket provided with an opening therein, and a coupling member associated with said extrusion and in communication with said opening, said coupling member being provided with fastening means, said fastening means being disposed out of alinement with said extrusion.

4. A radiator comprising a plurality of heat-dissipating units, a header member provided with a plurality of openings in one side thereof for communication with said units, the opposite side having an extruded portion in the form of a pocket provided with an aperture therein, a tubular member

disposed in communication with said aperture and attached to said extrusion.

5. A radiator adapted to be mounted on a tank, said radiator comprising a plurality of heat-dissipating units, a header member provided with a plurality of openings in one side thereof for communication with said units, the opposite side having an extruded portion in the form of a pocket provided

10 with an aperture therein and provided with a coupling member, a coupling member rigidly mounted upon said tank, and means for clamping said coupling members together, said means being disposed out of alinement

15 with said extrusion.

6. A radiator adapted to be mounted on a tank, said radiator comprising a plurality of heat-dissipating units, a header member provided with a plurality of openings in 20 one side thereof for communication with said units, the opposite side having an extruded portion in the form of a pocket provided with an aperture therein, a coupling member associated with said extruded portion, a similarly shaped coupling member mounted on said tank, said coupling members being provided with outwardly projecting openings therein out of alinement with said extrusion and adapted to receive threaded fastening means.

7. A radiator adapted to be mounted on a tank, said radiator comprising a plurality of heat-dissipating units disposed in side-by-side relation, each of said units being provided with an offset portion, a coupling member associated with each of said offset portions, and means disposed out of alinement with said offset portions for securing together the coupling members of adjacent

40 units.

8. A radiator adapted to be mounted on a tank, said radiator comprising a plurality of heat-dissipating units disposed in side-by-side relation, each of said units being provided with an offset portion, a coupling member associated with each of said offset portions, and means disposed out of alinement with said offset portions for securing together the coupling members of adjacent

units, the endmost of said units being provided with a coupling member relatively larger than said intermediately disposed coupling member, a similarly relatively larger coupling member associated with said tank, and means for clampingly engaging the coupling member of the endmost unit to the coupling member of the tank, said clamping means being disposed out of alinement with said offset portions and with said intermediately disposed coupling members.

9. A radiator adapted to be mounted on a tank, said radiator comprising a plurality of heat-dissipating units disposed in side-by-side relation, each of said units being provided with an offset portion, a coupling member associated with each of said offset portions, said coupling members being provided with offset ears each having an aperture therein, bolts disposed within said apertures for securing said coupling members together, the endmost of said radiating units being provided with a coupling member relatively larger than said intermediately disposed coupling member and provided with an offset ear member, a similarly relatively larger coupling member associated with said tank, bolts disposed within the aperture of said relatively larger coupling members, said last mentioned bolts being disposed out of alinement with said offset portions and with said intermediately disposed coupling members.

10. A radiator adapted to be mounted on a tank, said radiator comprising a heat-dissipating unit, a header member in communication therewith and provided with an extruded portion in the form of a pocket, means for establishing communication between said pocket and said tank, and means disposed without the area of projection of said header member and said extruded portion for detachably securing said header member to said tank.

In testimony whereof, I have hereunto subscribed my name this 12th day of November, 1920.

WALTER M. DANN.
